LUDWIG SCHÖN, OF ESSEN-ON-THE-RUHR, GERMANY, ASSIGNOR TO FRIED. KRUPP AKTIENGESELLSCHAFT, OF ESSEN-ON-THE-RUHR, GERMANY.

RELEASING DEVICE FOR OVERLOAD SWITCHES.

Application filed December 3, 1920. Serial No. 428,092.

To all whom it may concern:

Be it known that I, Dr. LUDWIG SCHÖN, residing at Essen-on-the-Ruhr, Germany, a citizen of the German Republic, have invented a certain new and useful Improvement in a Releasing Device for Overload Switches (for which I have filed an application in Germany January 6, 1919), of which the following is a specification.

10. This invention refers to a releasing device for overload switches in the case of which an automatic electromagnetic cut-out, operating in dependence upon the current intensity of the circuit to be interrupted, is adapted to gradually close by the actuation of a ratchet gear closing auxiliary circuit, the closing of which in turn causes the overload switch to enter into function.

20. An embodiment of the subject matter of this invention is shown by way of example in the annexed drawing in combination with an overload switch serving for the protection of a series motor.

25. Referring to this drawing, A denotes the magnet core of the overload switch provided with two exciting windings B and C wound to assist each other. Of these two windings, the one, B, is disposed within the main circuit containing the series motor D, while the other winding, C, is connected in an auxiliary circuit in shunt with the main circuit. A resistance F is interpolated between the one end of the exciting winding C and a point of the main E connecting the main current winding B with the motor D. To the lower 30 end of the magnet core A there is fixed a contact member a^1 affording the possibility of bridging a break disposed in the main circuit and consisting of two stationary contact members a^3 and a^4 . A spring a^2 adapted to act counter to the magnetic pull of the 35 overload switch is arranged to engage the contact member a^1 . The general conditions are such that the series winding B will be 40 enabled to open the overload switch A only at a very considerable overload (short-circuit). On the other hand, the winding C, disposed within the auxiliary circuit, and the 45 resistance F are so dimensioned that the

50 overload switch A will be opened by means of a current traversing the auxiliary circuit while keeping clear of the resistance F, and that, subsequently, the said overload switch A will be retained in the off position by a current traversing in series the exciting 55 winding C and the resistance F.

Two exciting windings H and H^1 are disposed in series within the main E connecting the main current winding B of the overload switch with the motor D. The said two 60 windings are oppositely wound on a magnet core G and are for their part so dimensioned that they are enabled to produce magnetic pulls of equal magnitude. On the core G there is in addition arranged a third winding 65 J short circuited on itself. The one of said exciting windings connected in series, H^1 , is adapted to be short-circuited by means of a main G^5 provided with a break. This latter is composed of a rigidly disposed contact member g^2 and a movable contact member g^1 fixed to the upper end of the magnet core G. A spring g^3 is adapted to engage the contact member g^1 , while with its other end said spring bears down on a stationary plate g^4 . 75 The exciting winding H is so dimensioned that when the current intensity does not exceed the normal rate its magnetic pull will not be sufficient to overcome the power exerted by the spring g^3 , while the moment an 80 overload current arises in the main E, the said magnetic pull will cause the magnet core G to move downwards, so that the spring g^3 will be compressed and the break g^1, g^2 in consequence opened.

85. A bolt g^7 , fixed to the lower end of the magnet core G and traversing the rigidly fixed magnet armature g^6 , is provided with a pawl g^8 adapted to cooperate with a ratchet wheel K in such a manner that each time the pawl g^8 causes a downward motion, the ratchet wheel K will rotate for the space of a tooth in the direction indicated by the arrow x . The said ratchet wheel K is keyed onto a shaft k^1 on which a switch arm k^2 , 90 provided with a contact member k^3 , is fixed. A spiral spring k^4 is secured, on the one hand, to the said arm k^2 and, on the other

hand, to the bearing (not shown) of the shaft k^1 , which spiral spring has the tendency to rotate both the arm k^2 and the ratchet wheel K backwards, counter to the direction indicated by the arrow α . The contact member k^3 mounted on the movable arm k^2 and connected by means of a main M with the one end of the exciting winding C of the overload switch, forms, conjointly with a stationary contact member k^5 connected for its part by means of a main N with the negative pole of the source of supply, a branch of the auxiliary circuit C M k^2 k^3 J k^5 N, containing the exciting winding C, by the closing of which auxiliary circuit the overload switch is put in function.

With the ratchet wheel K co-operates a pawl P formed by a two-armed lever, the one arm p^1 of which is acted upon by a magnet, arranged within the main E and adapted to operate when subject to overload, where-as a spring p^3 acting counter to the magnetic pull is adapted to engage the other arm p^2 of the said lever. The magnet Q and the spring p^3 are so designed that the magnet Q will be enabled to overcome the tension of the spring p^3 , and therewith the pawl P will be able to arrest the ratchet wheel K, only for such a length of time as the main E is traversed by an overload current.

When considering the manner of operation of the device hereinbefore described let it be assumed that the motor D is running and taking a current of normal intensity, and further that all the parts are in the position illustrated. In this position, the exciting winding H^1 is short-circuited by the main G^5 , the break g^1 g^2 of which is bridged, while both the pawl P, acted upon by spring p^3 , and the pawl g^8 , in its turn acted upon by spring g^3 , remain in consequence out of engagement with the ratchet wheel K. The switch arm k^2 maintains its open position, and the break a^1 , a^3 , a^4 of the overload switch A B C is bridged. The main circuit is now traversed by a current flowing from the positive pole of the source of continuous current supply across a^4 , a^1 , a^3 , B, E, Q, H, G^5 , g^1 , g^2 , G^5 , E, D to the negative pole.

If now for any cause whatsoever, say, for example in consequence of the motor D obtaining a mechanical overload, the intensity of current within the main circuit should happen to exceed a certain limit without, however, attaining that particular value at which the exciting winding B of the overload switch A B C enters into function, then the magnet Q will attract the arm p^1 of the pawl P, and this latter will thus come to engage the ratchet wheel K by means of its other arm p^2 . At the same time the magnet core G is drawn downwards by the magnetic pull exerted by the exciting winding H counter to the action of the spring g^3 .

This downward motion of the magnet core G opens the break, composed of the contact members g^1 , g^2 and appertaining to the main G^5 adapted to short-circuit the exciting winding H^1 . The current within the main circuit therefore now takes its course across the exciting windings H, H^1 connected in series. As a result, the magnetic pull exerted up to that moment by the exciting winding H on the core G is equalized, and is further temporarily replaced by the magnetic pull exerted in the same sense by the short-circuit winding J, in which there arises, when the field of the winding H is equalized, a powerful induction current.

The core G is thus enabled to complete its downward motion until it makes contact with the armature g^8 , and then returns, when the field of the winding J has disappeared, into its initial position under the action of the spring g^3 . In the course of the downward motion of the core G just described, the pawl g^8 engages the ratchet wheel K and rotates it forward for a tooth space, in the direction of the arrow α . At the same time the contact member k^3 fixed to the arm k^2 approaches the stationary contact member k^5 for one certain step. It is obvious that the damping action of the winding J will be all the more powerful,

the greater the intensity of the current which has traversed the main circuit and excited the winding H. On the conclusion of the said upward motion of the core G the contact members g^1 and g^2 again make contact and the exciting winding H^1 is again short-circuited. Thereupon the operation is repeated and continues while there is an overload in the main circuit until the contact members k^3 and k^5 make contact. As soon as this takes place, a current is caused to flow across the auxiliary circuit + C M k^2 k^3 k^5 N —, exciting the hitherto dead exciting winding C of the overload switch A B C and resulting in the interruption of the main circuit by breaking the contact between the member a^1 and the members a^3 and a^4 , whereupon the motor D is quickly brought to a stop. As, together with the main current, the excitation of the magnet Q disappears, the pawl P is brought out of engagement with the ratchet wheel K and the arm k^2 acted on by the spiral spring k^4 , returns into the initial position shown in the drawing, the ratchet wheel rotating in the direction counter to that indicated by the arrow α .

Notwithstanding, the exciting winding C still remains excited since a current is now caused to flow across + C F E Q, H, G^5 , g^1 , g^2 , E, D — which, in view of the dimensions indicated of the resistance F, suffices to retain the magnet core A in its upraised position and counter to the action of the spring a^2 , so that the main circuit is now prevented from again closing. Only

when, after the disturbing element has been removed, a hand cut-out disposed in the main circuit (though not shown) has been put in the off position, the exciting winding C is deprived of current and the overload switch returns into the position indicated. The said hand cut-out being again returned into the closed position, the operation may be repeated. The more powerful the overload current within the main circuit, the more rapid the motion will be executed by the magnet core G, and as a consequence the shorter will be the duration of the individual steps of the switching operation. The moment at which the arm k^2 by means of its contact member k^3 makes contact with the member k^5 and thus closed the auxiliary circuit containing the exciting winding C, thus depends upon the size of the overload prevailing in the main circuit in such a manner that a slight overload may be kept up longer than a great overload, a fact which entirely corresponds with the peculiar requirements of an intensely working motor service.

On the flow of the overload current ceasing before the contact members k^3 and k^5 have made contact then the magnet Q will release the arm p^1 of the pawl P, and this latter is brought out of engagement. Hereupon, the spiral spring k^4 draws the arm k^2 back into its position of rest so that any interruption of the overload switch is not liable to arise.

In this case of a very powerful overload current, such as will arise in the course of a short-circuit, the magnet core A is immediately attracted in consequence of the magnetic pull exerted by the exciting winding B and the main circuit thereby broken without the remaining portions of the releasing device being brought into action.

If it be desired to render variable, independent of the current intensity, the period of time passing from the commencement of the switching operation until the interruption takes place by the magnet core A, that may be effected by arranging the contact member k^5 to move along an arc of a circle around the axis of rotation of the switch arm k^2 .

As will be readily understood from the foregoing description, the subject matter of the invention excels in the simplicity of its construction while embodying reliability of service and the capacity to regulate the above-mentioned switching time within wide limits.

Claims.

1. An arrangement of the class described in combination with an overload switch comprising an electromagnetic periodic interrupter, said interrupter being included in the circuit to be broken and operating in dependence upon the intensity of this cir-

cuit, an auxiliary circuit and means operable by said interrupter for closing said auxiliary circuit step by step to cause said overload switch to function.

2. A device of the class described in combination with an overload switch comprising an automatic electromagnetic device connected in and operable in dependence upon the current intensity of the circuit to be broken, an auxiliary circuit operatively connected to said overload switch for controlling the same, a step by step ratchet mechanism and a switch operated thereby for closing said auxiliary circuit, said ratchet mechanism being operable by said automatic electromagnetic device.

3. A releasing device for overload switches comprising in combination with an overload switch an electromagnetic periodic interrupter having two series windings of equal magnetic intensity, means connecting said windings whereby when said interrupter is in closed position one of said windings is short circuited and when said interrupter is in off position said windings neutralize one another, an auxiliary circuit connected to said overload switch so as to control the same, a step by step circuit closing device for closing said auxiliary circuit and means operable by said interrupter for operating said circuit closing device.

4. A releasing device for use in combination with overload switches comprising an electromagnetic periodic interrupter included in and operated in dependence upon the current intensity of the circuit to be broken, said interrupter being provided with two series windings of equal magnetic intensity, means for normally short-circuiting one of said windings when said interrupter is in its closed position, said windings being neutralized when said interrupter is in the off position, said interrupter being provided with a short winding short circuiting on itself, an auxiliary circuit connected to said overload switch in such a manner as to operate the same, a switch for controlling said auxiliary circuit, means operated by said interrupter for effecting the closing of said switch, said short winding being provided for the purpose of extending the duration of the steps of the switching operation of said interrupter.

5. A device of the class described comprising the combination with an overload switch of an automatic electromagnetic device included in and operating in dependence upon the current intensity of the circuit to be broken, an auxiliary circuit operatively connected to said overload switch for controlling the same, a switch for closing said auxiliary circuit, a ratchet carrying the movable portion of said switch, a power accumulating member tending to retain the movable portion of said switch in its open po-
